UNITED STATES PATENT OFFICE.

GEORGE DELK, OF SOUTH MILWAUKEE, WISCONSIN, ASSIGNOR OF ONE-HALF TO
EMIL F. TSCHOHL, OF SOUTH MILWAUKEE, WISCONSIN.

RAIL FROG.

Application filed March 7, 1922. Serial No. 541,661.

To all whom it may concern:

Be it known that I, GEORGE DELK, a citizen of the United States, and resident of South Milwaukee, in the county of Milwaukee and State of Wisconsin, have invented certain new and useful Improvements in Rail Frogs; and I do hereby declare that the following is a full, clear, and exact description thereof.

10 My invention relates to a new and improved rail frog of the type which is adapted to be used in running a car back on to the railroad track after it has been derailed.

The general object of the invention is to 15 provide a simple device of this character, formed in a single integral piece, which may simply be laid upon the rail and will retain its position thereon while the car is pulled back on to the rails.

20 It is also within the scope of the invention to provide a frog which includes a plurality of parallel tracks which converge towards and merge into the surface of the rail, whereby the car wheel may be rolled directly onto 25 the frog and up on to the rail, regardless of the distance between the wheel and the rail.

In describing my invention, reference will be had to the accompanying drawing, in which

30 Figure 1 is a plan view of a section of a railroad track with my invention applied thereto.

Figure 2 is a side elevation of the same, and

35 Figure 3 is an elevational view taken on the line 3-3 of Figure 1.

In the drawing, I have illustrated two frogs, 5 and 6, applied to the two rails of the track, and constructed substantially 40 alike, except that one is adapted to be laid inside the rail, while the other is adapted to be laid outside thereof. Each frog is provided with a laterally extended integral flange 7, having at its outer end, a down- 45 turned lip 8, which is so shaped as to fit snugly over the rail 9. The lower inner edge of the frog is provided with an inclined shoulder 10, which is adapted to engage the rail flange 11, and in connection 50 with the flange 7 and lip 8 to hold the frog firmly in its proper position relative to the

rail. The upper surface of the frog is formed with one or more laterally inclined track portions 12 at the side of each of which is a groove 13 adapted to receive and guide 55 the flange of the car wheel. All of these track portions converge towards and merge into the surface of the rail to which the frog is secured, the inner end of the frog being downwardly inclined, as seen at 14. The 60 outer ends of the track portions 12 are extended, as at 15, in parallel relation to the direction of the road, and their upper surface 16 is inclined downwardly to a point which rests upon one of the ties 17. 65

In using my invention, a pair of frogs, 5 and 6, are laid upon the rails in front of the wheels of the car which has been derailed. The car is then propelled by any available power, so as to ride up on to the 70 inclined portions 15, and upon further advance will be readily carried along the laterally inclined portions 12, back on to the track. It will be seen that a railway frog has been provided for placing a derailed car 75 back upon the track in such a manner that the tread of the wheels rides upon the track portions of the frog and the weight of the car is removed from the flanged portion. It is well understood that the flanged portion of the railway car wheel is the weakest 80 portion and will not stand severe stresses as readily as the tread portion. The frog, forming the subject matter of this invention, is particularly designed to relieve the 85 flange of the unnecessary stresses usually imposed thereon by frogs of this type.

Thus it will be seen that I have provided a very simple and inexpensive appliance which may be carried on the train and will 90 be always available for use. The restoration of a derailed car may therefore be accomplished with the utmost facility.

While I have shown one specific structure by means of which the invention may be 95 carried out, it will be understood that minor changes may be made therein, without departing from the spirit of the invention.

I claim:

A railway frog comprising a series of laterally inclined track portions converging toward a single track portion adapted to be 100

2

mounted upon a railway track, said single track portion having an inclined terminal portion and having an integral depending flange adapted to fit over the rail, said 5 frog having a series of grooves formed between the successive track portions to guide the flange of the car wheel, whereby the flange of the car wheel is relieved of the

supporting stresses and said stresses are borne by the tread portion of such wheels. 10

In testimony that I claim the foregoing I have hereunto set my hand at Milwaukee, in the county of Milwaukee and State of Wisconsin.

GEORGE DELK.
